UNITED STATES PATENT OFFICE.

EDWIN M. ROSENBLUTH, OF PHILADELPHIA, PENNSYLVANIA.

ACETYLENE-GAS GENERATOR.

1,223,294.

Specification of Letters Patent.

Patented Apr. 17, 1917.

Application filed September 18, 1913. Serial No. 790,396.

To all whom it may concern:

Be it known that I, EDWIN M. ROSENBLUTH, a citizen of the United States, residing at Philadelphia, in the county of Philadelphia and State of Pennsylvania, have invented a certain new and useful Improvement in Acetylene-Gas Generators, whereof the following is a specification, reference being had to the accompanying drawings.

10 My invention relates to a generator of the type described in Letters Patent of the United States 1,025,648 granted to me May 7, 1912, and provides such a generator with a carbid casing and appurtenances adapted for coöperation with carbid cartridges which, as hereinafter described, include a flexible cover of textile fabric having a series of compartments independently charged with carbid so that the latter is equally distributed throughout the length of the cartridge when the latter is extended in the plane position in which it is formed, and also when it is bent to the annular position which it occupies in the carbid casing.

15 As hereinafter described, said water receptacle includes a main compartment adjacent the carbid chamber and an auxiliary compartment above said main compartment; and a water passageway leading from said main water compartment into the carbid casing is controlled by a rotary valve which also controls a gas passageway leading from said carbid casing to the atmosphere, the construction and arrangement being such

20 that when the gas passageway is opened the water passageway is closed and vice versa; said valve being rotatable by a rod extending from the main water compartment through the auxiliary water compartment

25 and having an operating handle exterior to the latter, and said rod carrying a valve controlling communication between said auxiliary compartment and said main compartment so as to place them in communication only when said water passageway leading from said main compartment to said carbid casing is closed.

30 However, said specific construction and arrangement of the water feeding mechanism is claimed in my copending application Serial 790,395, filed Sept. 18, 1913.

35 My invention includes the various novel features of construction and arrangement hereinafter more definitely specified.

40 In the drawings: Figure I is a vertical

sectional view of a generator conveniently embodying my invention.

Fig. II is a plan view of the carbid casing and base of the generator shown in Fig. I.

Fig. III is an elevation of the cartridge shown in section in Fig. I.

Fig. IV is a fragmentary horizontal sectional view taken on the line IV, IV in Fig. I.

Fig. V is a fragmentary vertical sectional view taken at right angles to the plane of section of Fig. I.

In said drawings; the generator has the base 1 including the condensate trap 2 cast in unitary relation with the feet 3 having the openings 4 by which it may be permanently connected with an automobile or other vehicle. Said trap has the gas inlet 6 at the top thereof and the condensate outlet 7 at the bottom thereof. The duct 10 leads from said trap 2, by way of the branch ducts 11 to respective branch condensing coils 12 and 13 through which the gas from the generator is delivered to the lamps or other gas condensing devices which are connected therewith, conveniently by the flexible tubing 15. Said coils are carried by said base 1 to which they are detachably secured by the bolt 16 and yokes 17 and 18 and have means including the nuts 20 detachably connecting said coils in communication with said ducts 11. It is to be understood that the moisture entrained in the gas passing from said inlet 6 and through the trap 2 and said coils 12 and 13 is condensed and the condensate gravitates to the bottom of said trap as indicated at 22 in Fig. I.

The carbid casing 24 has the central tubular column 25 with the gas outlet 26 at the bottom thereof, detachably secured therein by its screw thread 27 and the nut 28 and is detachably fitted to said base 1; the latter having the resilient gasket 30 surrounding said gas inlet 6 and retained by the ring 31 held by the screw 32 engaging said base 1, as shown in Fig. I, so as to seal the joint between said gas outlet 26 of the carbid casing 24 and the gas inlet 6 of said generator base 1.

The carbid 34 is supported in said carbid casing 24 in the removable cartridge 35 which is a folded web of textile fabric, primarily plane as shown in Fig. III and holding said carbid 34 equally distributed

110

throughout its length in the separate compartments conveniently formed by parallel lines of stitches 37. Said cartridge may be closed at the top, conveniently by the line 5 of stitches 38 shown in Fig. III, or it may be left open at the top if it is desired to use the cartridge 35 repeatedly with successive charges of carbid 34. In the latter case, the top of the cartridge being open 10 permits the ejection of the carbid ash. However, the casing of said cartridge 35 being inexpensive textile fabric such as cheese cloth, it is preferable to close the cartridges as shown in Fig. III, so as to prevent 15 accidental escape of the carbid during the preliminary handling of the cartridges; the latter being thrown away when the carbid charge thereof is depleted.

In order to facilitate the absorption of 20 water by the carbid 34 as the latter decomposes, I find it preferable to compress said cartridge 35 at the bottom of the carbid casing 24. In order to effect such compression, I provide the bowl 40 encircling the central 25 column 25 in said casing 34 but removable therefrom, said bowl being provided with the spiral spring 41 which is permanently attached thereto at its lower end. Such attachment is conveniently effected by the 30 brackets 42 which are soldered to said bowl and spring so as to leave a space between them for the passage of water. The upper end of said spring 41 bears upon the foraminous conical floor 43 of the dome 45 35 which extends into the water receptacle 46 and forms part of the bottom of the latter.

Said water receptacle 46 is arranged to detachably fit upon said carbid casing 24, and has the resilient gasket 47 held between 40 its bottom flange 48 and 49 resting upon the upper edge of said casing 24 so as to seal the joint between said casing and said water receptacle 46.

Said water receptacle 46 has the central 45 tubular column 51 in axial alinement with the column 25 in said carbid casing, and includes the main compartment 53, adjacent said casing, and the auxiliary compartment 54 above said main compartment, said compartments being separated by the diaphragm 55.

The valve casing 60 which is permanently set in the bottom of said main compartment 53 of the water receptacle has the water inlet 55 passageway 61 leading to the restricted water outlet 62 in the bottom of said valve casing and to the similar restricted water outlets 63 in fittings 64 which are also permanently set in the bottom of said receptacle 60 as indicated in Fig. I and connected with said valve casing 60 by the branch tubes 66. Each of said water outlets 62 and 63 is conveniently provided with a reciprocatory plunger 68 such as shown in Fig. I, arranged 65 to restrict the flow of water and to be lon-

gitudinally shifted to free any obstruction which may lodge in said outlets. It is to be understood that when said passageway 61 is in communication with said outlets 62 and 63 water is permitted to drip through said outlets into said bowl 40 and thence, through the central opening at the bottom thereof encircling the column 25, and thence to the bottom of the casing 24; the rounded surface thereof serving to distribute the water 70 radially into the textile fabric of the cartridge 35 through which it is absorbed into contact with the carbid 34 in the several compartments thereof.

Said water passageway 61 is controlled 80 by the valve plug 75 which is mounted to turn in said valve casing 60 through an arc of 90 degrees, to and from the position shown, such movement being limited by a stud on said plug encountering shoulders on 85 said casing. Said valve plug 75 has the stem 77 extending through the tube 78, permanently secured in said diaphragm 55 and in the top of the water receptacle 48, and has the operating handle 79 which is detachably secured thereon by the screw 80. Said handle 79 has the circular flange 81 overhanging the top of said tube 78 and the joint between them is sealed by the resilient 90 gasket 82.

Said valve stem 77 also carries the valve 84 which has a face of resilient material 85 (for instance leather) bearing upon the inner face of said tube 78 toward which said valve 84 is pressed by the springs 86. Said valve 84 is provided to control the water passageways 89 leading from said auxiliary water compartment 54 to the main water compartment 53, and it may be observed 100 that the construction and arrangement is 105 such that when the water passageway 61 from the main compartment to the carbid casing is closed, the water passageway 89 leading from said auxiliary compartment to said main compartment is opened as shown 110 in Fig. I, and vice versa.

Moreover, I provide a gas passageway from said carbid casing 24 to the atmosphere, controlled by the same valve means, so that any gas generated after the water is 115 shut off at said passageway 61 may escape directly to the atmosphere instead of through said condensing coils 12 and 13 to the lamps. Said passageway is shown at 91 in Fig. I, extending from the gas dome 45 120 through said valve casing 60 and the port 92 in said valve plug 75 and terminating in the gas vent nozzle 93 exterior to the water receptacle 48, and is closed when said plug 125 is turned to open said passageway 61.

Therefore, it may be observed that the generator above described includes a gas passageway from said carbid casing to the atmosphere; a water passageway leading from said main compartment of the water recep- 130

tacle into said carbid casing; a water passageway from said auxiliary compartment in the water receptacle to said main compartment, and valve means controlling said 5 gas and water passageways, so constructed and arranged that when the gas passageway is opened, the water passageway between said compartments is opened and the water passageway from said main compartment to said carbid casing is closed, and vice versa. It is to be understood, that the construction and arrangement above described regulates 10 and renders as uniform as possible the rate of flow of water into and through said bowl 15 40, and consequently insures the uniform supply of water to the several compartments of said cartridge 35, and the generation of gas therefrom.

As shown in Fig. I, the water receptacle 20 46 is provided with the reinforcing cap 95, which is permanently secured thereon, and has the inlet or filler tube 96 extending from the exterior of said receptacle 46 through the top thereof into the auxiliary water compartment 54 and is provided with a closure 98 which is eccentrically pivotally connected with said tube 96 by the pintle 99 which extends through the bearing 100 and carries at its lower end the abutment 101 for the 25 spring 102 which encircles said pintle and tends to press said closure 98 shut. It is to be understood that when it is desired to fill said receptacle 46 with water, said closure 98 may be raised by its knob 105 and turned 30 aside to uncover said tube 96 to permit water to be poured therein, and when said closure is returned to registry with said tube 96, it is tightly shut thereon by said spring 102. However, when said closure is opened, as 35 40 aforesaid, and the valve 84 turned to the position shown in Fig. I, the water passageway 89 leading from said auxiliary compartment 54 to said main compartment 53 is open so that both compartments of said 45 receptacle may be filled with water 106 through the inlet 96.

In order to avoid the creation of a partial vacuum by subsidence of the water 106 in the receptacle 46, which might interfere 50 with the gravitational feed of the water to the carbid, I provide the top of the receptacle 46 with an aperture 108 in communication with the air vent 109 opening through said cap 95 in communication with the outer atmosphere. It may be observed that said aperture 108 and vent 109 are out of alinement, so that if any water is forced through the 55 top of the receptacle 46 by back pressure of gas in the generator, it is caught in said cap 95 and subsequently gravitates back into the receptacle 46, instead of being thrown out of the generator as it would be if said aperture 108 communicated directly with the atmosphere.

60 65 However, the details of construction and

arrangement of the water receptacle such as herein shown form the subject matter of my copending application Serial No. 784,292, filed August 12, 1913, for Letters Patent of the United States.

Means are provided for detachably rigidly connecting said carbid casing 24 and water receptacle 46 with said base 1, including the screw threaded rod 111 depending in said water receptacle column 51 from the 70 top thereof, having the operating handle 112 provided with the resilient gasket 113 bearing upon the top of said cap 95 and sealing the joint thereat. Said rod 111 may be reciprocated longitudinally to facilitate the 75 engagement of the screw thread 116 at the lower end thereof with the screw thread 117 at the upper end of the stem 118 which extends in the carbid casing column 25 from the base 1, and extends through said trap 2 80 and carries at its lower end the closure 120 for said condensate outlet 7. Said closure 120 carries the resilient gasket 121 to seal said outlet when the connection between said rod 111 and stem 118 is tightened by rotation of said handle 112. In order to prevent 85 rotation of said stem 118 when engaged by said rod 111, said closure is provided with eccentric studs 125 extending in sockets 126 in said base 1 which hold spiral springs 127 90 pressing upon said closure 120 so as to automatically open the latter when said stem 118 is released by said rod 111.

The generator above described is operated as follows:—The generator being charged 100 with carbid, in the cartridge 35, and the valve handle 79 being turned to the position shown in Fig. I, the generator is in inoperative position because the water passageway 61 leading from the receptacle 46 to the carbid casing 24 is closed and the gas passageway leading from the carbid casing 24 to the atmosphere, through the valve plug 75, is open. In this position, the water passageway 89, leading from the auxiliary water compartment 54, to the main compartment 53 is open and, said auxiliary compartment being in communication with the atmosphere through the aperture 108 and vent 109, water 106 is free to subside and charge the main compartment 53. In thus charging said compartment 53, the interior of the latter is, of course, in communication with the compartment 54 through the water passageway 89 comprising the vertically disposed series of 105 110 115 120 125 130 openings in the tube 78 shown in Fig. I; so that the gaseous mixture of atmospheric air and water vapor which accumulates in the compartment 53, as the water is discharged from the latter, may escape into said compartment 54 from said compartment 53 when the latter is being charged. It being desired to operate the generator, the valve handle 79 is turned from the position shown in Fig. I, through an arc of 90 de- 130

4
grees. Thereupon, the water passageway 61 leading from the main water compartment 53 to the restricted outlets 62 and 63 being open, the water gravitates through said outlets upon the bowl 40 and thence to the carbide 34, decomposing the latter and generating gas which is forced by its own pressure upwardly through the central aperture in the conical floor 43 surrounding the column 25, thence between said columns 25 and 51 to the top of the column 25, thence downwardly between said column 25 and the rod 111 and through the interstices between the gas inlet tube 6 of the base 1 and the stem 118 of the closure 120 and through the gas outlet 26 into the trap 2 and thence through the ducts 10 and 11 to the condensing coils 12 and 13 and thence to the lamps or other gas consuming devices connected to the upper ends 15 of said coils, conveniently by flexible rubber tubes.

The ash residue of the decomposition of the carbide 34 is retained by the porous casting of the cartridge 35 so that it may be removed with the latter. The condensate 22 from the gas gravitates to the bottom of the trap as indicated and is automatically discharged therefrom whenever the closure 120 is opened by release of the stem 118.

30 If the operation of the generator is continued, without shutting off the water feed, (by returning the valve handle 79 to the initial position shown in Fig. I,) the water may be exhausted from the main compartment 53 to the level of the bottom of the water passageway 61. However, during such operation, the gas pressure gradually diminishes because of the diminishing rate at which the water gravitates through the outlets 62 and 63, consequent upon the lessening height and consequent pressure of the water in the main compartment 53; and such diminution in pressure may be manifested by the lessening brilliance of the 40 flames of the lamps. It may be observed that such diminishment in the gas pressure is characteristic of all generators which have a single supply of water the pressure of which diminishes as the water is consumed in decomposing the carbide. However, with my improved construction above described, the water pressure may be repeatedly restored to its original amount by momentarily returning the valve handle 79 45 to the "off" position shown in Fig. I, thus permitting the water from the auxiliary compartment 54 to recharge the main compartment 53 to its initial full extent. Moreover, it may be observed that when the 50 valve is in said position the water rises in the tube 78 to the level of the water in the upper auxiliary compartment 54, so that when the valve handle 79 is turned to the other position, which is the gas generating

position, the initial pressure of the water 65 is that incident to the height of the water in the main compartment 53 plus the height 70 of the water in said tube 78; but the latter only holds a small quantity of water which quickly subsides to the level of the water in the lower compartment 53 when the valve 75 80 85 90 95 100 105 110 115 120 125 130 135 140 145 150 155 160 165 170 175 180 185 190 position, the initial pressure of the water 65 is that incident to the height of the water in the main compartment 53 plus the height 70 of the water in said tube 78; but the latter only holds a small quantity of water which quickly subsides to the level of the water in the lower compartment 53 when the valve 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915

handle 79 from the position shown in Fig. I, through an arc of 90 degrees as above described.

It is to be particularly noted that the 5 central tubular column 25 of the carbid casing 24 extends far above the latter and is imperforate; because such construction compels the gas generated in said casing 24 to pass in a thin film between the central 10 tubular column 51 of the water receptacle and said column 25, to the top of the latter, and to pass downward in a film between said column 25 and the rod 111. Said gas is thus subjected to the low temperature 15 maintained by the water surrounding said column 51 so as to precipitate the greater portion of the condensate therefrom in position to return into operative relation with the carbid 34 by trickling down the outer 20 surface of said column 25. Such construction is not only advantageous in that it insures the separation of the entrained moisture from the gas but retains the bulk of such moisture in operative relation with 25 the carbid and thus permits of the generation of a larger volume of gas from a given charge of water than if the condensate were permitted to escape from the generator.

It is to be understood that I do not desire 30 to limit myself to the precise details of construction and arrangement above described, as it is obvious that various modifications may be made therein without departing from the essential features of my invention, 35 as defined in the following claims.

I claim:—

1. In an acetylene gas generator, the combination with a carbid casing, having an imperforate central tubular column extending 40 above said casing, with a gas outlet at the bottom thereof; of a water receptacle having a central tubular column and arranged to detachably fit upon said carbid casing, with said columns in loose telescopic 45 relation; and means for detachably connecting said casing and receptacle; whereby the gas generated in said casing is directed in a film between said columns and subjected to the low temperature maintained by the 50 water in said receptacle.

2. In an acetylene gas generator, the combination with a carbid casing; of a water receptacle arranged to detachably fit upon said carbid casing; means for detachably 55 connecting said casing and receptacle; and means arranged to compress carbid downwardly and outwardly in said casing, including an annular bowl having a central outlet and a spring; the upper end of said 60 spring being held by said water receptacle, and the latter having a water outlet overhanging said bowl.

3. In an acetylene gas generator, the com-

bination with a carbid casing, having a floor inclined downwardly from the center to the 65 circumference thereof, whereby water in said chamber gravitates downwardly and outwardly on said floor; of means arranged to compress carbid downwardly and outwardly on said floor, including an annular bowl having 70 a spring; and means arranged to introduce water between said bowl and floor; whereby the carbid in said chamber is continually pressed into coöperative relation with any water in said chamber. 75

4. In an acetylene gas generator, the combination with a carbid casing, having a floor which is lower at its outer portion than at its center; of means arranged to compress carbid downwardly and outwardly in said 80 casing, including an annular bowl having a water outlet, and a spring pressing said bowl toward said floor; and means arranged to supply said bowl with water; whereby the carbid in said chamber is continually pressed into coöperative relation with any water in said chamber. 85

5. In an acetylene gas generator, the combination with a carbid casing, having a central tubular column with a gas outlet at the 90 bottom thereof; of a water receptacle having a central tubular column and detachably fitted upon said carbid casing, with said columns in axial alinement; means for detachably connecting said casing and receptacle; 95 a removable cartridge in said casing, extending annularly around said central tubular column, including a folded web of textile fabric having transversely extending parallel lines of stitches forming separate car- 100 bid compartments in a circumferential series in said casing; means compressing said cartridge in concentric relation with said column, including an annular bowl and a spring encircling said column; means at the lower 105 end of said spring connecting it to said bowl so as to leave a space between them for the passage of water; and means controlling the supply of water from said receptacle to said bowl; whereby the carbid is maintained 110 equally distributed in concentric relation with said column and continuously pressed into coöperative relation with any water in said casing.

6. In an acetylene gas generator, the combination with a carbid casing having a floor which is lower at its outer portion than at its center; a central tubular column in said floor having a gas outlet at the bottom thereof; said outlet being above the region to 120 which water gravitates on said floor; a water receptacle detachably connected with said carbid casing; a removable cartridge, in said casing, extending annularly around said column, including a web of porous fabric hav- 125 ing separate carbid compartments, in a cir-

cumferential series in said casing; and means compressing said cartridge in concentric relation with said column including an annular bowl and a spring encircling said column; and means controlling the supply of water to said casing from said receptacle; whereby the carbid in said casing is compressed downwardly and outwardly in cooperative relation with any water in said 10 casing, and said gas outlet is continuously

maintained above the water level in said casing.

In testimony whereof, I have hereunto signed my name at Philadelphia, Pennsylvania, this tenth day of September, 1913.

EDWIN M. ROSENBLUTH.
